UNITED STATES PATENT OFFICE.

SAMUEL F. TAPMAN, OF JAMAICA, NEW YORK.

METHOD AND APPARATUS FOR RIVETING.

Application filed August 20, 1927. Serial No. 214,296.

The present invention relates to methods of riveting and deals more particularly with such methods when applied in service requiring rapid work and an unfailing uniformity of excellence of the finished product. A device *b* for applying power to the riveting plunger. In this instance, the power source is shown with a cylinder provided with a piston adapted to be moved under air pressure and controlled by hand lever *b'*. A

Where a great amount of riveting is to be done the expense of handling the materials in the drilling or punching, and riveting operations is a considerable proportion 10 of the total cost of the finished work and many forms of punches, drills and riveters have been designed in an effort to reduce the time required for doing the work. As a matter requiring further consideration, the 15 strength of the joint under shearing stresses requires that the piece be designed with a sufficient quantity of metal to compensate for that removed in the drilling or punching operations.

connecting rod b^2 is pivotally connected to a link b^3 which is pivoted at b^4 upon the stationary portion of the press. A suitable plunger a' is slidably carried in the upper 65 head of the bull press a and is connected, through link a^2 , to the pivot point of link b^3 and connecting rod b^2 . From the above description, it will be apparent that outward movement of connecting rod b^2 will cause 70 a downward movement of plunger a' and the desired riveting operation is thereby accomplished.

A slot a^3 is provided in the bearing for 75 the plunger in the upper head of the bull

20 This invention deals with these two factors and an object thereof is to provide a method and apparatus for riveting whereby the handling of the piece is reduced appreciably thereby cutting down the expense of the total
25 operation. It is proposed to eliminate the step of drilling and, instead, force the rivet through the pieces to be joined while the latter are highly heated.

A further object lies in preserving the original quantity of metal in the pieces, as well as forcing it under the rivet heads to cause it to fill all available space thereunder. In this manner the maximum strength of the joint is obtained as well as utilizing all of the metal in the pieces to be joined.

Other objects of the invention will be apparent as the description proceeds and reference will now be had, for a more detailed description of the invention, to the accompanying drawings wherein:

Figure 1 is a view in elevation, partly in section, showing a device in which the invention has been embodied in a known form of bull press, the work being in place, and the means for heating it bearing thereagainst to bring it to the desired temperature.

Figure 2 is a sectional view taken on line 2-2 of Figure 1 and looking in the direction of the arrows.

Figure 3 is a view in section taken on line 3-3 of Figure 2 and looking in the direction of the arrows.

55 Referring to the drawings *a* indicates a bull press of the usual form provided with

a device b for applying power to the riveting plunger. In this instance, the power source is shown with a cylinder provided with a piston adapted to be moved under air pressure and controlled by hand lever b' . A connecting rod b^2 is pivotally connected to a link b^3 which is pivoted at b^4 upon the stationary portion of the press. A suitable plunger a' is slidably carried in the upper head of the bull press a and is connected, through link a^2 , to the pivot point of link b^3 and connecting rod b^2 . From the above description, it will be apparent that outward movement of connecting rod b^2 will cause a downward movement of plunger a' and the desired riveting operation is thereby accomplished.

A slot a^3 is provided in the bearing for the plunger in the upper head of the bull press, and a pin a^4 carried by the plunger a' moves in this slot. 75

In securing the pieces together by means of the rivet, the former are placed in the proper position as shown in Figure 1 and indicated at *c*. A rivet *d* is placed at the head of the plunger *a'* and, when the work has been heated to the proper temperature, the plunger is moved downwardly to force the rivet through the highly heated work. 85

A device for heating the work and riveting includes a bracket e , carrying, pivotally, a guide member e' for an electrode holder e^2 . A forked lever e^3 is pivoted with the guide e' upon the bracket e and is formed with a rearwardly extending cam arm e^4 which is normally disposed in the path of movement of the pin a^4 . The electrode holder e^2 is provided with a head e^5 carrying diametrically disposed rollers e^6 . Springs e^7 aid the force of gravity in restoring the electrode and related parts to the normal position shown in full lines in Figure 2. These rollers engage the upper faces of the forked portions of lever e^3 , and permit relative movement between the head e^5 and forked lever e^3 when the latter is moved pivotally by the engagement of pin a^4 with cam e^4 . 90 95 100

In the downward movement of the plunger a' , the pin a^4 engages the cam e^4 and moves the electrode holder e^2 upwardly until the head e^5 engages the guide member e' . Continued movement of the pin then causes pivotal movement of the guide e' with respect to the bracket e and the resulting effect upon the electrode f is to move it away from the descending plunger a' . The sta-

tionary portion a^5 of the bull press a is connected to a suitable source of electricity g which, preferably, is of low voltage and capable of supplying an extremely high current. The electrode f is also connected to the other side of this current supply and insulated from the conducting parts of the mechanism which are carried by the press.

When the electrode f is moved under influence of the spring e^7 into engagement with the work c and the rivet d , the circuit is closed through the work and rivet, and the current flow therethrough heats them to the desired temperature. Due to the fact that the area of contact between the electrode f and rivet d is relatively small, a proportionately smaller amount of current will pass through the rivet and, as a consequence, the rivet will not be heated as highly as the work. The time of contact of the electrode with the rivet and work is designed to be sufficiently long to bring the work to an extremely high temperature, at which the rivet may be forced through with little difficulty. The heating of the rivet, during this time, is sufficient to bring it to a cherry heat and permit it to be headed in the proper manner as it is forced through the work.

It will be seen that performing the operation in the manner described above results in removing no metal from the work. By reason of the condition of the work and rivet when the latter is forced through the former and headed, the metal around the rivet will be forced into intimate contact with every available portion thereof. This increases the strength of the joint against shear and the resulting work is much stronger due to this fact, as well as the fact that no metal has been removed from the work.

The operation described above can be performed in less than six seconds and it will be quite apparent that a great saving results in the handling of the work, since it is unnecessary to perform the drilling operation. The invention is not to be construed as limited to the form of apparatus shown and described herein, since many constructions may be provided to perform the steps in the method embodied herein, and the specific mechanism described has been used merely as an example of one form in order that the invention might be described more clearly.

I claim as my invention:

1. The method of riveting comprising, placing the work in the desired position, heating it to a working temperature, heating the rivet, forcing the rivet through the work, and heading the rivet.
2. The method of riveting comprising, placing the work in the desired position, heating it to a working temperature, heating the rivet to a temperature, lower than

that of the work, forcing the rivet through the work, and heading the rivet.

3. The method of riveting comprising, placing the work in the desired position, heating it to a working temperature, heating the rivet simultaneously, forcing the rivet through the work, and heading the rivet. 70

4. The method of riveting comprising, placing the work in the desired position, placing the rivet over the work in a position to be forced into place, simultaneously heating the rivet and work to different temperatures, forcing the rivet through the work, and heading the rivet to compress the work between the heads thereof. 75

5. A device of the character described comprising means for holding the work, means for applying heat thereto to bring it to a working temperature, means for heating the rivet, means for forcing the rivet through the work, and means for heading the rivet. 85

6. A device of the character described comprising means for holding the work, means for applying heat thereto to bring it to a working temperature, means for heating the rivet to a temperature lower than that of the work, means for forcing the rivet through the work and means for heading the rivet. 90

7. A device of the character described comprising means for holding the work, means for applying heat thereto to bring it to a working temperature, means for heating the rivet simultaneously, means for forcing the rivet through the work and means for heading the rivet. 100

8. A device of the character described comprising means for holding the work, an electrode, means for placing the electrode over the portion of the work to be riveted and engage the rivet simultaneously, means for passing current from the electrode through the work and rivet to heat them to the desired temperatures, means for forcing the rivet through the work and means for heading the rivet. 105

9. A device of the character described comprising means for holding the work, an electrode, means for placing the electrode over the portion of the work to be riveted and engage the rivet simultaneously, the area of the rivet engaged by the electrode being smaller than the area of the work engaged thereby, means for passing current from the electrode through the work and rivet, a smaller quantity passing through the rivet than through the work due to the different contact areas thereof, means for forcing the rivet through the work and means for heading the rivet. 115

This specification signed this 18th day of August, A. D. 1927.

SAMUEL F. TAPMAN.
